US0D1095025S

(12) **United States Design Patent** (10) **Patent No.:** **US D1,095,025 S**
(45) **Date of Patent:** **** Sep. 30, 2025**

(54) **STORAGE BOX**

(71) Applicant: **Hangzhou GEMO Technology Co., Ltd.**, Hangzhou (CN)

(72) Inventor: **Zitong Zhao**, Hangzhou (CN)

(73) Assignee: **Hangzhou GEMO Technology Co., Ltd.**, Hangzhou (CN)

(**) Term: **15 Years**

(21) Appl. No.: **29/907,356**

(22) Filed: **Jan. 5, 2024**

(30) **Foreign Application Priority Data**

Jul. 10, 2023 (CN) 202330430479.2

(51) **LOC (15) Cl.** **03-01**

(52) **U.S. Cl.** ..... **USPC D3/273**

(58) **Field of Classification Search**

USPC D3/239, 242, 273, 274, 275, 276, 281,
D3/282, 290, 291, 304, 305, 307, 308,
D3/309, 312, 315; D6/663, 671.1, 703,
D6/703.2, 703.3; D24/209, 210

CPC G06F 1/20
